US0D1050038S

(12) **United States Design Patent** (10) **Patent No.:** **US D1,050,038 S**
(45) **Date of Patent:** **** Nov. 5, 2024**

(54) **PORTABLE POWER STATION**

(71) Applicant: **Guangdong Zhihe Electronics Technology CO., LTD.**, Dongguan (CN)

(72) Inventors: **Wanlong Zhang**, Nanyang (CN); **Hongyin Xing**, Zaoyang (CN)

(73) Assignee: **Guangdong Zhihe Electronics Technology CO., LTD.**, Dongguan (CN)

(**) Term: **15 Years**

(21) Appl. No.: **29/860,077**

(22) Filed: **Nov. 16, 2022**

(30) **Foreign Application Priority Data**

Nov. 10, 2022 (EM) 015002832-0001

(51) **LOC (14) Cl.** **13-02**

(52) **U.S. Cl.**

USPC **D13/110**; D13/103

(58) **Field of Classification Search**

USPC D13/110, 103, 107, 108, 19, 118, 119, D13/182, 199

CPC Y02T 90/00; H01M 6/00; H01M 6/10; H01M 6/14; H01M 10/52

(57) **CLAIM**

The ornamental design for a portable power station, as shown and described.

DESCRIPTION

FIG. 1 is a front, right and top perspective view of a portable power station, showing our new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the portable power station that form no part of the claimed design.

1 Claim, 8 Drawing Sheets
